HARRY F. SCHWARTZENBERG, OF CHICAGO, ILLINOIS, ASSIGNOR TO WILLIAM H. MINER, OF CHICAGO, ILLINOIS.

DRAFT-YOKE FOR RAILWAY-CARS.

1,136,053.

Specification of Letters Patent. Patented Apr. 20, 1915.

Application filed March 9, 1914. Serial No. 823,283.

To all whom it may concern:

Be it known that I, HARRY F. SCHWARTZENBERG, a citizen of the United States, residing at Chicago, in the county of Cook and State of Illinois, have invented a certain new and useful Improvement in Draft-Yokes for Railway-Cars, of which the following is a full, clear, concise, and exact description, reference being had to the accompanying drawings, forming a part of this specification.

My invention relates to improvements in draft yokes for railway cars, and more particularly draft-yokes for tandem-arranged draft gear.

In tandem draft gear, as is well understood, a plurality, preferably two, separated compression resisting members are placed in tandem arrangement within a yoke member, the yoke member being provided with a lateral opening for each compression resisting member. In such arrangement the portion of the yoke forming the front recess to receive the front compression resisting member is employed in compressing both compression resisting members in pulling as well as in buffing action of the draft rigging, while the members of the yoke rearwardly thereof are employed only in pulling movement of the draft rigging to compress the rear compression resisting member of the draft gear. In buffing action the rear compression resisting member is compressed by the bar or thimble or separating member within the yoke disposed between the front and rear compression resisting members. As the shocks in buffing movement are greater than the strain in pulling movement, the forward portion of the yoke in tandem-arranged draft gears is required to bear more severe shocks and strains than the rear portion of yokes employed with tandem-arranged draft gear.

The object of my invention is to provide a draft yoke in which the weight and strength of the forward and rearward portions thereof may be more nearly in proportion to the shocks and strains they are required to bear than in constructions heretofore known and employed.

In the drawings forming a part of this specification, Figure 1 is a plan view of a draft yoke embodying my invention; Fig. 2 is a side elevation partly in vertical longitudinal section on line 2—2 of Fig. 1; Fig.

3 is a cross-section on line 3—3 of Fig. 2; Fig. 4 is a cross-section on line 4—4 of Fig. 2.

Referring to the drawings, the numeral 5 indicates the forward member of a draft-yoke, and the figure 6 the rearward member thereof, the said yoke being designed especially for gears in tandem arrangement. The forward member 5 comprises upper and lower limbs 7 and 8, respectively, a transverse member 9 rearwardly connecting said limbs and preferably integral therewith, the said limbs 7 and 8 each being preferably provided along their outer edges with longitudinal, preferably integral reinforcing ribs 10—10. At their forward ends the said limbs are joined at either edge by the preferably integral side plates 11—11, forming with the limbs 7 and 8 a hollow box-like opening 13 to receive a draw-bar, the said plates having transverse perforations 12—12 to receive a coupler key to engage the yoke to a draw-bar. The connecting member 9 at the rear end of the limbs 7 and 8 is preferably provided with a forward bearing post 15 and a rearward bearing post 16, each of said posts having preferably an opening 17 therein and a transverse space 18 between them. At its rear end the forward member 5 of the yoke is provided with upper and lower rearwardly opening slots 19 and 20, respectively, to receive the free ends of the limbs 21 and 22 of the U-shaped rear member 6 of the yoke, each of said limbs being provided near its forward end with a perforation 23 registering with adjacent perforations 24—24 in the connecting member 9 of the forward member 5 of the yoke to receive the rivets 25—25 which connect the rear member 6 to the forward member 5 of the yoke. In preferable construction the rear member 6 is provided with the filler block 26, which is secured to the connecting member 27 between the limbs 21 and 22 by the rivet 28 passing therethrough. Thus there is formed a transverse opening 29 to receive the rear compression resisting member and a transverse opening 30 to receive the front compression resisting member of a tandem-arranged draft gear. In preferable construction the front member 5 is of cast steel, and the rear member 6 of wrought iron.

I claim:

A tandem draft yoke for railway draft riggings comprising two members the front one

of which is provided with upper and lower limbs connected by an integral hollow post open on the sides thereof, said member being horizontally slotted at the ends of said post,
5 the other of said members comprising a **U**-shaped strap having the free ends thereof secured in said slots, and short rivets extend-

ing through said members to hold the st connected with the first named member.

HARRY F. SCHWARTZENBERG.
